UNITED STATES PATENT OFFICE.

JOHN BARBERIE, OF BROOKLYN, NEW YORK, ASSIGNOR TO BARBERIE LOCOMOTIVE APPLIANCE COMPANY, A CORPORATION OF NEW YORK.

SAFETY APPARATUS.

No. 825,289.

Specification of Letters Patent.

Patented July 10, 1906.

Application filed February 26, 1906. Serial No. 302,831.

To all whom it may concern:

Be it known that I, JOHN BARBERIE, a citizen of the United States, and a resident of Brooklyn, in the county of Kings and State of New York, have invented certain new and useful Improvements in Safety Apparatus, of which the following is a specification, taken in connection with the accompanying drawing, which forms a part of the same.

This invention relates to safety apparatus particularly adapted for application to locomotives and electrically-propelled cars.

The accompanying drawing illustrates diagrammatically the embodiment of this invention upon an electrically-propelled car.

In the illustrative embodiment of the invention shown in the drawing 1 is a track device or trip pivoted at 2 and fixed upon the road-bed to swing into and out of operative position and is usually used in connection with a semaphore. (Not shown.) When this semaphore is set at "danger," the trip 1 is in position (shown in full lines) and is adapted to contact with the destructible cap 3, mounted upon the end of the hollow piston-rod 4, working within the cylinder 5. This cylinder is divided into two parts by the plate 6, which is firmly secured upon the interior of the cylinder by the screws or other fastening means 7. The piston-rod 4 passes through an air-tight aperture in the plate 6, and its upper end carries a piston 8. In communication with a lower portion 9 of the cylinder 5 is a train-line pipe 10, within which is mounted the emergency-valve 11, which is normally seated in the position shown in full lines by the train-pipe pressure, but when properly operated in the manner hereinafter to be described moves from the position shown 40 to the stops 12 12. The upper portion of the cylinder 5 is connected below the piston 8 by means of pipe 13, pipe 14, three-way valve 15, pipe 16, with the main reservoir 17. Pipe 13 is also in communication with pipe 18, valve 45 19, and with the upper portion of the emergency brake-cylinder 20. The upper portion of cylinder 5, above the piston 8, is connected by means of pipes 21 22 and three-way valve 15 with the main reservoir 17 and is normally charged with air under pressure therefrom when the valve 15 is in position. (Shown in full lines.) Pipe 22 also connects with the lower portion 23 of the cylinder 20, which is also normally charged with air by

means of pipe 24. This three-way valve 15 55 may be of any well-known type.

Within the cylinder 20 and adapted to reciprocate between the openings of pipes 18 and 24 is mounted a piston 25, having a rod 26 and a spring 27, which normally forces the 60 piston 25 upward away from the opening of pipe 24. The piston-rod 26 is elongated and passes through a check-cylinder 28. Mounted upon the lower portion of the piston-rod 26 is a second piston 29, having a flap-valve 30. 65 Oil is usually placed within this check-cylinder through the opening 31, which is closed by a cap 32.

A part of my apparatus also includes the ordinary brake-cylinder 33, which operates 70 the brake-shoes in the usual well-known manner. To obtain some of the fluid-pressure used in operating the brakes to simultaneously shut off the motive power when the brakes are applied, I connect pipe 34 to the 75 brake-cylinder and at its opposite end connect it with the cylinder 35. Within this latter cylinder there is a piston 36, having a rod 37, to the outer end of which is connected a contact-head 38. Mounted within the 80 cylinder on the opposite side from the opening of pipe 34 is a spring 39, which normally presses the contact 38 outward to complete the circuit between the wires 39 40, and it will be seen that when pressure enters the 85 brake-cylinder 33 this circuit is broken by the cylinder 35. These wires 39 and 40 are a part of the ordinary multiple-control circuit 41, which passes through the ordinary controller-boxes 42 42, which operate in a well-known manner by the control-switches 43 43. Two terminals 44 44 of this multiple-control circuit 41 are located adjacent to each other and adapted to be electrically connected by means of the contact-plate 45, carried by the 90 valve-arm 19, for the purpose hereinafter to be described. The multiple-control circuit 41 is shown broken at 46 and 47 to be connected with the master-controllers of the several cars making up the train all in a well-known 95 manner.

The operation of the parts so far described is such that if the engineer or motorman fails to see the danger-signal the trip 1 will engage the destructible cap 3 as the car passes 100 over this portion of the track and will break the same, permitting the air-pressure to escape from the train-line pipe 10 through

the lower portion 9 of the cylinder 5, and thence through the hollow piston-rod 4 by means of the openings 48 48. This will immediately apply the brakes of the car in the 5 well-known manner and cut off the motive power by operating the cylinder 35. It is often desirable, however, to permit the motorman to pass by the danger-signal into the 10 next block without upsetting the signal. In this application the vertically-movable portion of the safety apparatus the destructible cap, which is adapted to contact with the fixed trip 1, is raised and lowered into operative position by mechanism which will now 15 be described.

With the valve 19 and contact-piece 45 in the position shown in full lines the motorman moves the valve 15 into the position shown in dotted lines, which exhausts the 20 pipes 21 24 and upper part of cylinder 5 and lower part of cylinder 20 and at the same time permits the fluid-pressure to flow from the main reservoir in the direction indicated by the arrows up through pipes 16, 25 valve 15, pipe 14, pipe 13, around into the cylinder 5 beneath the piston 8 and will in an obvious manner cause the same to move from the position shown until the piston contacts with the lugs 49 49. At the same time 30 the fluid-pressure is operating to move the piston 8 a portion of the same will flow into pipe 18 through valve 19 into the upper portion of the cylinder 20 above the piston 25. The pressure in this cylinder causes the piston-rod 26 to move against the action of the 35 spring 27 and in the retarding-cylinder 28 will force the oil contained within the same to flow through the by-pass 50. The openings of this by-pass are so proportioned as to 40 require an appreciable interval of time to elapse, about five or ten seconds, before the piston-rod 26 reaches its extreme downward movement, where its end 51 is adapted to contact with the head 52 of the emergency- 45 valve 11 and immediately open the same. When it is desired to reset the safety device, the handle of the valve 15 is moved into position, (shown in full lines,) which exhausts the 50 pipes 13 18 and that portion of the cylinders 5 and 20 communicating with the same and permits the air from the main reservoir 17 to again flow through the three-way valve 15, the pipes 22, 24, and 21 to the respective portions of the cylinders 5 and 20, which will 55 cause the destructible cap 3 to be lowered into a position where it is adapted to be operated by the next succeeding trip 1 should the motorman fail to see the danger-signal. At the same time the piston 25 is moved in the 60 direction indicated by the arrow it carries with it the piston-rod 26, the piston 29, and the flap-valve 30, which in this movement of the parts swings downward and permits the oil to pass readily through the opening 53 65 into the lower portion of the check-cylinder

28 without forcing the same to flow through the by-pass 50. It will be readily understood that this arrangement of by-pass and flap-valve retards the downward movement of the piston-rod 26 and its head 51, but permits of the parts being readily retracted without any appreciable retarding action. 70

In my safety apparatus, when it is desired to bring the destructible cap 3 into an inoperative position to escape the trip 1 there is an appreciable interval of time before the head 51 of the piston-rod 26 contacts with the head 52 of the emergency-valve 11, due to the check-cylinder retarding the movement of this piston-rod. This is a very valuable improvement in the art, as it permits a motorman who has stopped his train within a short distance of the trip 1 and who desires to pass the same to do so without cutting off his motive power by operating his valve 15, permitting the fluid-pressure to pass into the pipes 13 and 18 and cylinders 5 and 20 in the manner previously described. When this is done, the piston-rod 4, on which is mounted the destructible cap 3, is immediately forced 80 upward and the piston-rod 26 and head 51 likewise immediately start to descend. The latter, however, is retarded, as previously described, so that the motorman can by his controller-handle 43 apply power to his car, so as 85 to pass the fixed trip 1. If he then immediately turns the three-way valve 15 so as to exhaust pipes 13 and 18 and the respective portions of cylinders 5 and 20, with which they communicate, and at the same time permit air under pressure to pass through pipes 16, 22, 24, and 21 into the cylinders 5 and 20, the destructible cap 3 will be immediately placed in position where it can be operated by the next fixed trip 1, and at the same 90 time the head 51 of the piston-rod 26 will be stopped in its descent toward the head 52 of the valve 11 and retracted, all of which will be done without interrupting the control of the motive power of the train. If, however, 95 after operating the three-way valve 15 so as to raise the destructible cap 3 into its inoperative position the motorman applies power to the car, permitting it to pass a fixed stop 1, and forgets to move back the three-way 100 valve 15 into the position shown in full lines, in about five or ten seconds the head 51 of the piston-rod 26 will contact with the emergency-valve 11 and instantly bring the train to a full stop, and at the same time fluid-pressure will pass into the brake-cylinder 33 in the well-known manner in this art, and a portion of the same will pass through pipe 34 to the cylinder 35, causing the piston 36 to move against action of the spring 39 and move the contact-piece 38, thereby breaking the electrical connection in the multiple-control circuit 41. By this construction the motorman has full control of his train even 105 when passing the danger-signal, and this con- 110

trol continues for about five or ten seconds, a sufficient time to permit him to operate the valve 15, so as to again place the safety apparatus into its operative position, failure 5 to do which will, as previously pointed out, after an interval of five or ten seconds bring the train to a full stop by the opening of the emergency-valve 11 and cutting off the motive power.

10 If my safety apparatus is used in an electric train of two or more cars operated by means of a multiple-control circuit, the motorman leaving, say, car 1, to operate the train from what was the last car, he will first 15 close the valve 19 to break the connection of the upper portion of cylinder 20 with the main reservoir 17 through the pipes 14, 16, and 18. At the same time that this is done the multiple-control circuit 41 is also interrupted by the plate 45, carried by the valve 19, being moved from the contacts 44 44. The three-way valve 15 is then operated so as to place the main reservoir 17 in communication with the cylinder 5 through pipe 13. 20 This position of the valves 15 and 19 permits of the piston 8 in the cylinder 5 being forced upward without, as is normally the case, at the same time forcing downward the piston 25 in the cylinder 20. When the 25 parts are in this position, the spring 27 will keep the head 51 of the piston-rod 26 from contacting with the emergency-valve 11. This throws out of operation the safety apparatus on this car as the other safety apparatuses on other cars should have been thrown out, except the one on the car from which the train is being controlled. To operate the train from what has been the last car, the motorman must open the valve 19 so as to place 30 the cylinder 20 in communication with the main reservoir 17 through the pipes 14 and 16 and three-way valve 15 and at the same time make electrical contact between the contact-pieces 44 44 of the multiple-control circuit 41 and the plate 45. The valve 15 is 35 then operated to exhaust the pipes 13, 14, and 18 and to place pipes 22, 21, and 24 into communication with the main reservoir, so as to permit the pressure from this reservoir 40 forcing the destructible cap into its operative position and at the same time charging the lower portion of the cylinder 20. In this position of the parts the train is adapted to be controlled from this car, it being readily seen 45 that only a single safety apparatus need be lowered into its operative position when the train is in motion and that one is upon the operating-car.

As a check upon the motorman to determine the care with which he observes signals, I preferably blow into the destructible cap 3 or otherwise mark the same with a serial number or other means of identification, so that a record of them can be kept. After 55 one of these caps has been destroyed through

failure of the driver to see a signal he can immediately operate the three-way valve 15 and close the valve 19, so as to move the piston-rod 4 until the openings 48 48 within the piston-rod 4 are within and closed by the 70 fixed plate 6. This prevents further escape of the fluid-pressure from the train-pipe 10 and permits of the ready application of another destructible cap in place of the one broken without being interfered with by escaping pressure. As soon as the brakes are set by the cap engaging with the fixed trip 1 the operator can, as previously stated, retract the piston 4 by means of three-way valve 15 and valve 19 and connections previously described and prevent the loss of more than a few pounds pressure from the train-pipe. It will thus be seen that should a train be stopped in a position so close to the fixed trip 1 that the movable portion of the 80 safety apparatus actually touched the fixed trip without setting the brakes it is possible to pass the trip with full control of power and that the train cannot be run for more than five or ten seconds without placing the 85 safety apparatus in a position to automatically bring the train to a standstill if for any reason the motorman fails to see the signal.

Having thus described my invention in connection with an electrically-propelled car, 95 to the details of which I do not desire to be limited, what I claim as new, and what it is desired to secure by Letters Patent, is set forth in the appended claims.

1. In a safety apparatus, means to actuate 100 the safety apparatus and apply the brakes, means for placing the safety apparatus in an inoperative condition and means for insuring a limited interval of time between the movement of the safety apparatus into its inoperative condition before the application of the brakes.

2. In a safety apparatus, means to actuate 105 the safety apparatus and apply the brakes, means for placing the safety apparatus into an inoperative condition and means for applying the brakes if the safety apparatus is left in its inoperative condition.

3. In a safety apparatus, means to actuate 110 the safety apparatus and apply the brakes, an electric control for the supply of motive power to the car on which the safety apparatus is mounted, means for placing the safety apparatus into an inoperative condition, and for interrupting the electrical control after an 115 interval of time.

4. In a safety apparatus adapted to set the brakes when in an operative condition, means 120 for placing the safety apparatus into an inoperative condition so as to permit the passage of a danger-signal, and means for preventing the brakes being set until the lapse of an appreciable interval of time after the 125 passage of the danger-signal.

5. In a safety apparatus, a closure device 130

in communication with the air-brake pipes, means for moving said closure device out of operative condition and at the same time actuate means which will apply the brakes, and additional means for retarding the action of the aforesaid means.

6. In a safety apparatus of the class described which is normally adapted to apply the brakes after the apparatus has been brought into its inoperative condition, means for preventing the application of the brakes for an appreciable interval of time to permit of the safety apparatus being returned to its operative condition.

7. In a safety apparatus adapted to set the brakes when in an operative position, means for placing the safety apparatus into an inoperative position so as to permit the passage of the danger-signal, and means for preventing the brakes being set until the lapse of an appreciable interval of time after the passage of the danger-signal.

8. In a safety apparatus, adapted to be moved into and out of its operative position and when in its operative position adapted to set the brakes, additional means for setting the brakes when the safety apparatus is in its inoperative position, said second means only acting to apply the brakes after an appreciable interval of time has elapsed after the safety apparatus has been brought into its inoperative position.

9. In a safety apparatus, a control-circuit adapted to be interrupted upon the application of the brakes, means for applying the brakes and interrupting the control-circuit when the safety apparatus is in its operative position and additional means for applying the brakes and interrupting the control-circuit when the safety apparatus is in its inoperative position.

10. In a safety apparatus, a control-circuit adapted to be interrupted upon the application of the brakes, means for applying the brakes and interrupting the control-circuit when the safety apparatus is in its operative position and additional means for applying the brakes and interrupting the control-circuit when the safety apparatus is in its inoperative position, said means adapted to actuate the brakes only after an appreciable interval of time after the safety apparatus has been brought into its inoperative position.

11. In a safety apparatus, a movable part, a track device, means for moving the movable part out of position for engagement with the fixed trip, and means to apply the brakes adapted to operate after an appreciable interval of time if the movable part is not replaced in its operative position.

12. In a safety apparatus, having an operative part mounted near the track, a coacting part carried on the car, means for moving the coacting part out of and into position for engagement with the fixed part near the track

and means adapted to operate after an appreciable interval of time to apply the brakes upon failure to reposition the coacting part.

13. In a safety apparatus, a track device, and a movable trip, means for moving the movable trip to and from operative position in relation to the track device and means to apply the brakes upon failure to reposition the movable trip.

14. In a safety apparatus, track device, movable trip means for moving the same into and out of operative relation to the track device and means, including a retarded element for actuating the brakes upon failure to reposition the movable trip.

15. In a safety apparatus, a track device, a closure device in direct connection with a train-line pipe and means for moving said closure device into and out of relation with the track device without cutting out the motive power.

16. In combination with a safety apparatus, a numbered or otherwise-designated destructible member for the purpose set forth.

17. In combination with a safety apparatus, a numbered frangible cap for the purpose set forth.

18. In a safety apparatus, a closure device in communication with the air-brake pipes, means for moving said closure device out of operative position and at the same time actuate means which will apply the brakes, and additional means for retarding the action of the aforesaid means.

19. In a safety apparatus, a closure device, in communication with the air-brake pipes, means for moving said closing device out of operative position, means for preventing loss of air from said pipe when said closure device is removed from its operative position and additional means for applying the brakes and means for retarding the action of said last-mentioned means.

20. In a safety apparatus, a closure device in communication with the air-brakes, a piston, a hollow piston-rod, a cylinder, means mounted in the cylinder for closing the opening in the hollow piston-rod when the closure device is in its inoperative position, an emergency-stop in the train-pipe, means for operating said emergency-stop, after an appreciable interval of time after the closure device has been brought into its inoperative position.

21. In a safety apparatus, a control-circuit, a closure device in communication with the air-brakes and an emergency-stop in the train-pipe, means for moving the closure device into its inoperative position, means for operating the emergency-stop, means for retarding the last-mentioned means, the parts being so arranged and proportioned that when the closure device is brought into its inoperative position to pass a signal and thereafter immediately lowered into its operative position, the means adapted to oper-

ate the emergency-stop will approach the stop but will not actuate it nor will the control-circuit be broken, thereby permitting the motorman to have perfect control of his car.

5 22. In a safety apparatus of the class described which is normally adapted to apply the brakes after the apparatus has been brought into its inoperative position, means for preventing the application of the brakes for an appreciable interval of time to permit of the safety apparatus being returned to its operative condition.

23. In a safety apparatus, of the class described which is normally adapted to apply the brakes after the apparatus has been brought into its inoperative position, a control-circuit and means for preventing the application of the brakes and the interruption of the control-circuit for an appreciable interval of time after the safety apparatus has been brought to its inoperative condition.

24. In a safety apparatus mounted upon a car, a portion of which is adapted to coact with a coöperating part near the track, means for moving a portion of the safety apparatus into and out of its operative position, a valve in the train-pipe, means to operate the valve when the safety apparatus is in its inopera-

tive position and means for delaying the opening of the valve in the train-pipe said means including a cylinder, piston and by-pass.

25. In a safety apparatus, including a control-circuit, the control-circuit and safety apparatus being mounted upon a car, a portion of the safety apparatus being adapted to coact with a coöperating part upon the track, means for moving a portion of the safety apparatus into and out of its operative position, a valve in the train-pipe, means for operating the valve and interrupting the control-circuit, means for delaying the opening of the valve in the train-pipe and delaying the interruption of the control-circuit, said means including a cylinder, piston, and by-pass.

26. In a safety apparatus, a track device, a train-line pipe, a closure device on the end of the pipe, and means for moving the pipe and closure device into and out of relation with the track device without cutting out the motive power.

JOHN BARBERIE.
